UNITED STATES PATENT OFFICE.

JOHN WILLIAM NASMITH, OF HEATON MERSEY, MANCHESTER, ENGLAND.

COMBING MACHINE.

Application filed August 9, 1927, Serial No. 211,828, and in Great Britain March 1, 1927.

In the original Nasmith combing machines, as in many previous machines a single feed roller resting on the lower jaw of the nipper was employed, with the object, that when 5 the nipper opened in moving forward to the detaching rollers the tips of the fibres forming the nipper tuft should be presented directly into the nip of the said rollers to ensure a perfect piecing and utilize the full 10 forward motion of the rollers by enabling them to seize the tips of the said tuft very early in their forward movement. This is well shown in the drawing to my British patent specification 16001/01. It will be 15 obvious that if a second roller were mounted on the top of the roller F of the said drawing and the lap passed between them the tips of the projecting tuft would be less satisfactorily presented to the nip of the 20 rollers D, d and would in fact touch the roller D low down so that it would have to turn some distance before the tips could reach the nipping point between the two rollers. This would interfere with the 25 excellence of the piecing especially with the shorter cottons, and also retard the entry of the top comb into the lap, as the detaching rollers must take up a certain amount of slack before pulling the tuft into the top 30 comb.

The single feed roller and plate are very practical and many thousands of apparatuses so constructed are at work, but there remains the fact that the lower side of the lap must slide over the stationary nipper 35 plate, and it is a desideratum that the advantages of the two roller feed which avoids frictional sliding of the lap at any point, and the advantages of the roller and plate feed, 40 which presents the tuft in the most efficient manner to the nip of the detaching rollers, should be combined in one apparatus. It is the object of my present improvements to provide such an apparatus and to this end 45 a nipper plate is combined with a pair of feed rollers the nip of which is substantially on a plane with the upper face of the plate. That is to say the roller nip is sufficiently 50 near to the plate surface to fulfill its function of a roller feed whilst avoiding sliding

contact between the lap and plate. Means are provided for giving the rollers bodily movement to correspond with the movement of the plate, and the usual ratchet motion may be employed to rotate the rollers at the 55 desired period, for feed purposes.

In the British patent specification No. 188,611 is described apparatus whereby the feed draws back a short length of lap before the nipper closes, to avoid accumulation of 60 good fibres behind the top comb with the subsequent withdrawal of such fibres as waste. The two roller feed, the object of these present improvements, can be very 65 beneficially applied to this type of apparatus, which had proved very satisfactory in practice, or to an apparatus wherein this drawback principle is not resorted to, but the said feed in two modifications will now be fully described in connection with apparatus 70 in which this draw back is employed, reference being had to the accompanying drawings wherein:—

Figure 1 is a partial section through one 75 head of a Nasmith comber.

Figure 2 is a partial front elevation of the nipper.

Figure 3 is a plan view of the nipper plate and bottom roller.

Figure 4 is a side elevation partly in section showing a modification wherein the lower feed roller is moved back positively to effect the drawback, and

Figures 5 and 6 are fragmentary detail 85 views of parts shown in Figure 5.

Referring first to the modification of Figures 1, 2, and 3 the combing cylinder is represented at C and D, d are the detaching rollers. The nipper bridge B is bolted at each end to nipper cheeks K hinging on the 90 adjustable nipper pivot N. To the bridge is secured the bottom nipper jaw, 1, which swings to and fro between the radii 2 and 3, receiving its motion from the usual operating shaft through the connecting rod 4 hinged 95 on the stud 5 which is secured in the cheeks K. For clearness the upper nipper jaw and arms J Figure 2 hinging on the pin 6 is not shown in Figure 1. F is the top feed roller resting on the bottom feed roller f, the nip- 100

per jaw shown in plan in Figure 3 is cut out so that the bottom feed roller can be dropped so as just to clear the cylinder needles and in this way the point of contact between 5 F and f is only slightly higher than in the old arrangement where a single roller rests on the nipper plate and the tuft is correctly presented to the nip of the roller D d as approximately indicated by the heavy dotted 10 line Figure 1. The roller f is carried in the bearings 7 adjustable on the bridge B.

Also hinged on stud 5 is the lever 8 having hinged to its upper end on the pin 9 the rod R at liberty to slide freely in the projection 15 10 cast on the back of K. The rod R at a given point in the forward swing of the nipper comes in contact with the pin P secured in the fixed but adjustable frame 11 (Figure 2) that carries the nipper pivots N. 20 The contact of the rod R with pin P, near the end of the forward movement of the nipper, moves the lever 8 round its pivot 5 and set screw 12 is carried away from the face 13 of cheek K against which it rests normally. 25 This movement but in the opposite direction is communicated to the bearing 14 of the feed roller F, which is adjustable on the rod 15 by screw 16, the rod 15 being hinged at 17 on the lever 8. The feed roller F therefore, 30 in addition to its rotation by the usual ratchet (indicated at 18 Figure 2) receives a bodily forward movement, when the nipper swings backwards the rod R leaves the pin P and allows screw 12 under influence of 35 spring 19 to again contact with face 13 so that the roller F is drawn bodily backwards rotating the roller f an amount which can be regulated by the screw 12 and in this way by very simple means the advantages of a 40 draw back feed are secured and combined with the advantages of a double roller.

The spring 19 serves the double purpose of holding 12 securely against face 13 until forced therefrom by contact of R and P and 45 putting the necessary pressure on the top feed roller F through the lever 20 hinged on pin 21 secured in cheeks K and carrying bowls 22 pressing on the rod 15. The distance of the nip of the feed rollers F f from 50 the lip of the nipper can be adjusted either by readjusting the bearings 7 of roller f or by moving bearing 14 on rod 15 or by both.

It will be obvious that if the "drawback" before referred to—which is effected by the 55 particular swinging relation described of cheeks K and lever 8 by their accessories of rod R and spring—is not desired, the top roller F can easily be arranged to swing with the said cheeks and the nipper plate, and an 60 extended description of such an arrangement is deemed unnecessary.

Where the nature of the fibre or other 65 circumstances make it expedient, in applying the "drawback" before referred to, the two roller feed may be modified by mounting

the two rollers in one moving member which draws them back together. From the foregoing description means for doing this in various ways could be employed but the method now to be explained with reference 70 to Figures 4, 5, and 6 of the drawings gives very good results.

Referring now to Figure 4, and where necessary to the detail Figures 5 and 6, two nipper cheeks K are provided, one of which 75 is seen in Figure 4, C is the usual combing cylinder and D one of the detaching rollers. F and f are the feed rollers, and 1 the lower nipper jaw which swings in an arc, the limits of the swing thereof being indicated by the 80 broken lines 2—3, this swinging motion being effected upon the pivot N by the connecting rod 4 hinged on the stud 5. The upper nipper jaw is omitted for clearness, but a pin whereon it is carried is shown at 6. 85

In the frame (not shown) which carries the pivot N is fixed the pin P, and each nipper cheek K carries a pin 21 on which is hinged a lever 23 forked at the lower end 24 to receive a bearing bracket 14 for the upper roller F, see the detail Figure 4. This bearing bracket 14 is slightly adjustable on a rocker bar 25 pivoting on a pin 26 carried by the lever 23 and to the tail end of this bar 25 is anchored the tension spring 19. On 90 the lever 23 is formed the projecting face 27 which serves as a contact piece and on a lug 28 cast on a cheek K is the adjustable screw stop 29. Lever 23 also carries an adjustable screw 30 in the position shown in Figure 4 95 where the end of the said screw may make contact with the pin P on the machine framing.

The lower roller f of the roller pair is carried in bearings 31 fixed to the front face 32 105 of a lever 23, each bearing being formed with the cup 33 to receive the brass bush of a neck of the shaft of the lower roller f. Both rollers F and f are therefore borne by the levers 23 and partake equally of the 110 movement of the said levers.

In operation as the nipper jaw 1 swings forward and assumes the position shown in the drawing Figure 1, around the center N, the screw stop 30 comes against fixed pin P, 115 thus causing each lever 23 to turn slightly around its center 21. This movement of the levers causes the roller pair F and f to swing forward bodily, to an extent which is adjustable by means of the screw 29, and such adjustment will be effected as desired in the actual operation of the apparatus, to allow of the bodily movement of the roller pair F and f in advance of the movement of the 120 nipper jaw 1. When the movement of the 125 nipper jaw 1 is reversed the spring 19 comes into operation and drawing up the tail of the rocker bar 25, the levers 23 again assume their original position, the contact face 27 again coming upon the limiting stop 29. 130

There is therefore a definite amount of draw-back imparted to the roller pair F and f in relation to the nipper jaw 1, the extent of the "drawback" depending upon the adjustable screw stops already referred to.

As will be seen, the spring 19 not only serves to return the roller pair F and f to its original position with the desired drawback, but it also serves to provide top pressure on the upper roller F to give the necessary grip to the sliver held in the nip of the said roller pair. The nipper jaw is recessed as shown to an extent sufficient to allow of the desired maximum movement within the said recess 15 of the lower roller f.

I claim:—

1. In a combing machine, a swinging nipper plate and a pair of feed rollers adapted to swing with the said plate, the nip of the roller pair being substantially flush with the upper surface of the said plate, and means for imparting rotary motion to the said rollers.

2. In a cotton combing machine, a swinging nipper plate and a pair of feed rollers adapted to swing with the said plate, the nip of the roller pair being substantially flush with the upper surface of the said plate, means for imparting rotary motion to the said rollers, means for carrying the upper roller of the roller pair independently of the swinging nipper plate but in contact with the lower roller, and means for imparting bodily movement to the said upper roller.

3. In a cotton combing machine, a swinging nipper plate and a pair of feed rollers adapted to swing with the said plate, the nip of the roller pair being substantially flush with the upper surface of the said plate, means for imparting rotary motion to the said rollers, a member on which the upper roller is borne, a recess in the nipper plate in which the lower roller is borne positioned and in which the said lower roller may rotate, the upper and lower rollers being in frictional contact, and means for imparting bodily motion to the upper roller.

4. In a cotton combing machine, a swinging nipper plate and a pair of feed rollers adapted to swing with the said plate the nip of the roller pair being substantially flush with the upper surface of the said plate, a ratchet gearing to give rotary motion to the upper roller as it moves bodily forward with the nipper plate, a member on which the upper roller is borne, a recess in the nipper plate in which the lower roller is positioned and in which the said lower roller may slide, the upper and lower rollers being in frictional contact, and means for imparting bodily motion to the upper roller and thus also to the lower roller.

5. In a cotton combing machine, a swing-

ing nipper plate, and a pair of feed rollers adapted to swing with the said plate, the nip of the roller being substantially flush with the upper surface of the said plate, means for imparting rotary motion to the said rollers, 70 a member on which the upper roller is borne, a recess in the nipper plate in which the lower roller is slidably positioned, the upper and lower rollers being in frictional contact, a swinging member bearing the nipper plate, 75 and means for imparting bodily motion to the upper roller and thus to the lower roller, from the said swinging plate bearing member.

6. In a cotton combing machine, a swinging nipper plate and a pair of feed rollers adapted to swing with the said plate, the nip of the roller pair being substantially flush with the upper surface of the said plate, means for imparting rotary motion to the said rollers, a member on which the upper roller is borne, a recess in the nipper plate in which the lower roller is slidably borne, the upper and lower rollers being in frictional contact, a swinging member bearing the nipper plate, a lever fulcrumed midway of its length the fulcrum moving with the said swinging member, to the lower end of which lever the upper roller bearing member is pivoted, a rod pivoted to the upper end of the lever and slidably borne by the nipper plate bearing swinging member, a fixed stop against which the end of the said rod abuts on the swinging of the said swinging member, and spring means for 100 maintaining the said swinging member and the upper end of the rod actuating lever in close but adjustable contact until separated by the forward swing of the plate bearing swinging member.

7. In a cotton combing machine, a swinging nipper plate and a pair of feed rollers adapted to swing with the said plate, the nip of the roller pair being substantially flush with the upper surface of the said plate, means for imparting rotary motion to the said rollers, means for carrying the two rollers in one swinging member but independently of the swinging nipper plate and in frictional contact with each other, and means for imparting bodily movement to the said upper roller and lower rollers which movement is of a desired path and speed relation to those of the nipper plate.

8. In a cotton combing machine, a swinging nipper plate and a pair of feed rollers adapted to swing with the said plate, the nip of the roller pair being substantially flush with the upper surface of the said plate, means for imparting rotary motion to the said rollers, a swinging member bearing the nipper plate, levers pivoted on cheeks which comprise the said swinging member, bearings for the upper roller said bearings being carried by arms pivoted to the 130

levers, spring means attached to one end of each such arm to apply pressure to the upper roller and to retain the levers in their extreme backward position until constrained to move against the spring tension, cup bearings for the lower roller, said bearings being carried by the upper roller bearing carrier and adjustable stops to limit the movement of the levers in both directions around their

pivots, one of the said stops serving as constraining means to cause the roller bearing end of the pivoted levers to move forward when the swinging nipper jaw moves forward.

In testimony whereof I have hereunto set my hand.

JOHN WILLIAM NASMITH.
